UNITED STATES PATENT OFFICE.

JAMES E. FARRELL, OF NEW BEDFORD, MASSACHUSETTS, ASSIGNOR TO T. C. ENTWISTLE COMPANY, OF LOWELL, MASSACHUSETTS, A CORPORATION OF MASSACHUSETTS.

PNEUMATIC LINT-CLEARER FOR WARPING-MACHINES.

1,339,182.

Specification of Letters Patent.

Patented May 4, 1920.

Application filed November 24, 1919. Serial No. 340,349.

To all whom it may concern:

Be it known that I, JAMES E. FARRELL, a citizen of the United States, residing at New Bedford, in the county of Bristol, 5 State of Massachusetts, have invented a certain new and useful Improvement in Pneumatic Lint-Clearers for Warping-Machines, of which the following is a specification, reference being had therein to the 10 accompanying drawings.

My invention has relation to warping machines, and comprises a traveling blower disposed above the yarns and operating to direct a blast or current of air in different directions through the yarns, combs, and drop-wires for the purpose of clearing lint away from the same.

Heretofore, the lint accumulating on warping machines has been a source of constant trouble, as by collecting in the combs and later being carried forward by the yarns, adhering to the latter so as to form "slugs" or bunches in the finished cloth; also, by clogging the drop-wires so that the 25 stop-motion mechanism is rendered ineffective to arrest the winding. The customary method of fanning the link from the bed of the machine, *i. e.*, by the use of a fan in the hands of an operator, is unsatisfactory and ineffective. Mechanical fans and suction devices have been used, but in their 30 use the fibers of cotton have been caused to become wrapped and bent about the yarns, drop-wires, and other parts, in such manner as not to be dislodged, owing to the current of air moving always in a fixed direction.

In my invention, a blast or current of air is produced by a blower, preferably a fan of 40 the usual electrically driven type, preferably (though not necessarily in all cases) suspended above the warping machine, traversed across the machine laterally, and from time to time adjusted automatically to 45 change the direction of the flow of air produced by its action, as by being rotated step by step about a vertical axis. The means for producing the blast of air may be varied through the range of equivalents. The 50 blower is adjusted to deliver its blast at an oblique angle, so that in virtue of the progressive adjustments a current of air

will be directed to all parts of the bed from different angles, thus thoroughly and efficiently loosening and clearing away all accumulated lint therefrom. 55

In the accompanying drawings, Figure 1 is a front elevation of a warping machine embodying my invention.

Fig. 2 is a sectional view of same on line 60 2, 2, of Fig. 1, like characters having reference to corresponding parts in both figures.

In the drawings is illustrated so much of a typical warping machine as is necessary 65 for an understanding of my invention. Upon suitable stands 1, 1, erected above the bed of the warping machine, is supported a traverse screw formed with the customary double screw-thread thereon, one end of the 70 shaft of said screw being shown at 3. Said traverse screw revolves in bearing-sleeves 4, 4, fixed in the upper extremities of stands 1, 1, and is rotated through the bevel gears 5, 5, by means of shaft 7, which in turn 75 is driven by bevel gears 6, 6, from the slow-motion drive-mechanism. Surrounding traverse screw 3 is a sleeve 9, fixedly supported upon the inner ends of bearing-sleeves 4, 4, and provided with a longitudinal slot to admit the traverse dog 10, carried by the traversing collar 11 which surrounds said sleeve and is adapted to slide 80 along the same. A ratchet-wheel 12 is pivoted to turn in a horizontal plane upon the 85 under side of said traversing collar 11. Two downwardly projecting lugs 13, 13, on said ratchet receive a pintle attached to the bail 14, from which latter is suspended on trunnions the fan 15. A guard 16 is provided 90 about the blades of said fan 15. Hooked pawls 17, 17, are carried by arms 18, 18, depending from the bearing-sleeves 4, 4. The said pawls by engaging with the teeth of the ratchet 12 at the end of each traverse 95 operate to shift the fan 15 angularly by causing a partial rotation of the ratchet and fan about the vertical pivot connecting the ratchet-wheel with the collar 11. A knife-switch 19 controls the electric current which 100 drives fan 15; the knife-blade of said switch is secured to the pedal rockshaft so that the current flows only when the warping machine is running.

In the operation of my invention, the blower is automatically set in action as soon as the warper is put on high speed. The pivotal connection of the fan casing to the supporting bail 14 permits the fan 15 to be swung to vary the degree of inclination with respect to the horizontal. The fan is shifted angularly at the end of the traverse in each direction by means of the hooked pawls 17, 17, under which the toothed portion of the ratchet-wheel 12 is caused to pass, the said pawls acting alternately through their engagement with the teeth of said ratchet-wheel to cause a partial or step-by-step rotation of the fan-supporting ratchet-wheel 12 around the pivot connecting it with the traversing collar 11 as the fan begins its traverse toward the other end of the machine. Thus the blast of air is directed at various angles, toward the front and back combs *a* and *b*, the drop-wires *c*, and the yarns *d*, with the effect of keeping the parts named clean and clear of the lint which accumulates and wraps itself about them.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but

What I claim as my invention is,—

1. The combination, with a warping machine, of a traveling blower, and means to change the direction of its blast from time to time to cause the latter to blow obliquely through the yarns in various controlled directions.

2. The combination, with a warping machine, of a blower mounted above the path of the yarns, means for causing it to travel back and forth across the latter, and means to change the direction of its blast from time to time to cause the latter to blow obliquely through the yarns at various angles.

3. The combination, with a warping machine, of a blower pivoted to allow direc-

tion of its blast obliquely through the yarns at various angles with respect to the horizontal, and means for traversing it back and forth transversely of said path.

4. The combination, with a warping machine, of a traveling blower pivoted to allow adjustable inclination of its blast obliquely with respect to the horizontal through the yarns, and means for rotating said blower in a horizontal plane to cause the air-current to blow in various controlled directions.

5. The combination, with a warping machine, of a traveling blower, and means to control the direction of its blast to cause the latter to blow obliquely at various angles at different times, for the purpose of clearing the yarns and drop-wires.

6. The combination, with a warping machine, of a traveling blower, and means to control the direction of its blast to cause the latter to blow obliquely at various angles at different times, for the purpose of clearing the drop-wires and combs.

7. The combination, with a warping machine, of a blower, traversing means for moving said blower back and forth transversely of the machine, and means to adjust it step by step as it traverses to cause its blast to sweep the machine in different directions with an inclined blast.

8. The combination, with a warping machine, of a blower, traversing means for moving said blower back and forth transversely of the machine, means to adjust it step by step as it traverses to sweep the entire machine with an inclined blast, and means to actuate said blower only when the machine is running on high speed.

9. The combination, with a warping machine, of a fan, a support therefor, a traverse screw for said support, a ratchet-wheel connected with said fan, pawls at each end of said traverse screw adapted to engage with said ratchet-wheel for rotating said fan step by step around a vertical axis, and means for driving said fan operable only when the said warping machine is running at full speed.

In testimony whereof I affix my signature.
JAMES E. FARRELL.
